Atty.

UNITED STATES PATENT OFFICE

CHARLES LOFMAN, OF RIVERSIDE, ILLINOIS, ASSIGNOR TO S. KARPEN & BROS., OF CHICAGO, ILLINOIS, A CORPORATION OF WEST VIRGINIA

MATTRESS AND MATTRESS MANUFACTURE

Application filed March 23, 1931. Serial No. 524,717.

This invention relates particularly to mattresses and the manufacture thereof; and the primary object is to provide for improved tufting of mattresses.

5 The invention is illustrated in the accompanying drawing, in which—

Fig. 1 is a broken plan view of a mattress constructed in accordance with the invention; Fig. 2, a broken sectional view 10 taken as indicated at line 2 of Fig. 1; and Fig. 3, a fragmentary view of the casing-top employed.

15 The invention is shown applied to a mattress having a filling which comprises a body of springs and layers of cotton or the like covering the springs. However, the invention may be used in connection with mattresses having any suitable filling.

In the illustration given, A designates a 20 filling comprising a spring-structure A' and layers of cotton, or the like, A², over the spring-structure; and B designates a casing comprising a quilted border B' and casing-tops, or covers, B².

25 The spring-structure A' shown is of the type in which coil springs are encased in fabric-cells and are connected by ties 1, if desired.

The top and bottom fabrics B² which 30 cover the broad sides of the mattress are connected with the boxing, or border, B' by means of corner-seams 2.

The fabrics B² are provided at selected 35 points throughout their area with pairs of eyelet-stitchings 3. These stitchings are provided by first marking the fabric at selected points, and then stitching the eyelets on the fabric, preferably by means of an eyelet-stitching machine devised to accomplish the purpose.

40 While it is unnecessary to describe the eyelet-stitching machine in the present application, it may be stated that each eyelet is formed by means of upper and lower 45 thread-carrying needles which have essen-

tially an annular movement, as well as a reciprocating movement, while the stitching progresses. Thus, the eyelet-stitchings form an annulus on the fabric at both sides thereof, as will be understood from Figs. 2 50 and 3. The fabric within the eyelet, designated 3^a is partially destroyed by the eyelet-stitching operation.

The tufting is accomplished, in the example illustrated in Fig. 2, by thrusting a 55 long heavy needle through one of the upper eyelets of a pair, passing the needle downwardly through the mattress and outwardly through the corresponding eyelet of the lower fabric, and then returning the needle 60 through the other eyelets of the pairs. The needle carries a suitable tie 4, which may be a heavy cord, or tape. The cord is cut and the ends joined together by a knot 4^a. The endless loop may then be shifted in the eyelets to bring the knot inside of the mattress. The looped ends of the tie thus engage the 65 top and bottom fabrics B², the members of the tie passing through the eyelets.

The tufting may be performed by passing 70 the needle wholly through the mattress, as illustrated; or, it may be performed by means of a curved needle which engages the filling in the mattress, but without passing wholly through the mattress, as is well 75 known in the art.

The improved method enables sewed eyelets to be used economically, in lieu of metal eyelets. By the improved method, it is unnecessary to cut openings in the casing-fabric. The eyelet-stitching may be performed upon the imperforate fabric, the selected points being simply marked in advance of the eyelet-stitching operation to insure a desired arrangement, or pattern, in the tuft- 80 85 ing.

What I regard as new, and desire to secure by Letters Patent, is:

In the manufacture of mattresses, the 90 steps which comprise: eyelet-stitching a fab-

ric to provide, at selected points throughout the area of the fabric, pairs of stitched eyelets, thus a providing casing-top; constructing a mattress having said casing-top as a part of the casing; and tufting the mattress by passing a needle and tie carried thereby through the fabric within the circle of one stitched eyelet of a pair and returning the same through the fabric within the circle of the other stitched eyelet of the pair, and suitably anchoring the tie to the body of the mattress.

CHARLES LOFMAN.
